UNITED STATES PATENT OFFICE.

THOMAS J. MAYALL, OF READING, MASSACHUSETTS.

MACHINE FOR SEWING CORDAGE.

SPECIFICATION forming part of Letters Patent No. 239,968, dated April 12, 1881.

Application filed April 15, 1880. (No model.)

To all whom it may concern:

Be it known that I, THOMAS J. MAYALL, of Reading, Massachusetts, have invented a new and useful Improvement in a Machine for Sewing Cordage to Form Shoes, and for other similar purposes, of which the following is a specification.

In Spain, and perhaps other European countries, it has been the custom to make soles for 10 shoes by winding twisted or braided strands of hemp, jute, or other similar and suitable fiber of considerable thickness into the form of a shoe-sole, and then, by means of an eye-pointed awl of sufficient length (about eight or 15 ten inches) and of about the thickness of a common loom-shuttle spindle, to carry another similar strand of the fibrous material transversely through all the convolutions of the strand previously wound up in a flat coil to 20 become a shoe-sole, from edge to edge, beginning at the heel or toe, and continuing these crossings near enough to each other to give the sole the required solidity the whole length of it, the cross-strands being drawn up as 25 closely as can be done by hand.

The object of my invention is to provide a machine, to be driven by any suitable power, by which an attendant of ordinary intelligence can work in the cross-strands heretofore worked 30 in by hand with the awl, as described, to produce the soles with much greater rapidity than the work can be done by hand-labor, and produce a more durable and satisfactory sole as a result.

35 In the accompanying drawings, which form a part of this specification, Figures 1 to 6 are general views of a machine constructed in accordance with the invention, Fig. 1 being an isometrical perspective view; Figs. 2 and 3, 40 views in elevation from opposite sides; Figs. 4 and 5, views from opposite ends, and Fig. 6 a plan view. Figs. 7 and 8 are sectional views in planes at right angles to each other, showing the bed for containing the sole and the 45 parts in immediate connection with said bed; and Figs. 9, 10, 11, and 12 are views, in plan and cross-section, of a bundle of cordage loosely wound into a sole and of a finished sole, respectively.

50 The same letters indicate like parts where they occur on all the figures.

The various devices are supported in a suitable frame, *a*, and power is conveyed to a driving-shaft, *b*, by a belt running on a pulley, *a'*, which is loose on the shaft, but can be made 55 to engage the fixed wheel *a*² so as to revolve it and the shaft *b* when required.

The shaft *a* communicates motion, by means of the bevel-gears *c d*, to cross-shaft *e*, which operates the working parts of the machine, and 60 which is therefore designated herein as the "main shaft."

The sewing of the loosely-wound cordage or strands of fibrous material into a sole is effected by an eye-pointed needle, (which carries 65 a binding-strand transversely through the cordage,) in connection with means for locking the loop carried through by the needle, and devices, hereinafter more fully set forth, for clamping the sole and feeding it forward a 70 suitable distance at each reciprocation of the needle.

The shuttle, which carries a second strand for locking that carried by the eye-pointed needle, is operated by the cam *f*, fixed on the 75 main shaft *e*. This cam has a groove of irregular shape, as shown in Fig. 3, in which works the roller *e*². The roller is carried at the end of a guide-lever, *f'*, which is pivoted at the end *e*³ to the machine-frame, and is connected 80 at its outer end, by the link *f*², with an arm, *f*³, of a rock-shaft, *f*⁴. This rock-shaft is supported in bearings parallel to the driving-shaft *b*, and on its opposite end is fixed an arm, *f*⁵, which is jointed by a slot-and-pin connection 85 to the shuttle-carrier *f*⁷, so as to reciprocate the same. The shuttle-carrier is guided by a slotted guide-piece, *f*⁸, the upper surface of which is hollowed to form the race for the shuttle *f*⁹. The race is provided with a cover, 90 *t*, which is at *t'* provided with a hole for the passage of the needle.

The needle-bar *h* is supported at its rear end by and moves in a dovetail groove in a block, *h*¹, which rests on one of the top rails of the 95 frame of the machine. The forward end of the needle-bar rests on a block, *h*², which, in turn, rests and slides on a beam, *h*³, below it, which beam is supported in its proper position in the machine by the rods or bars *h*⁴, themselves 100 suspended from the under side of the top rails of the machine. From the forward end of the

needle-bar h a guide-loop, h^5 , reaches down and around the beam h^3 , and, sliding on it, keeps the forward end of the needle-bar in its proper alignment. In the forward end of the needle-bar, and in direct alignment with it, is firmly fixed an eye-pointed needle, j . This needle is ordinarily about eight or ten inches in length and about an eighth to three-sixteenths to one-quarter of an inch in diameter. The eye 10 of this needle will admit a strand of twisted or braided fiber in size about equal to the diameter of the needle.

Above the needle-bar, and resting on a standard supported by the frame of the machine, is 15 a spool, j' , for the fibrous strand to be carried by the needle, and on other similar standards tension-pulleys, (marked respectively j^2 and j^3), around which the strand passes.

On the needle-bar h is fixed an adjustable 20 arm, s^2 , which reaches upward between the spool j' and the tension-pulley j^2 to about half the height of the tension-pulley j^2 , and is provided with an eye through the upper part of it, in which the strand of fibrous material to be 25 woven into the sole is carried. When the needle-bar moves backward, withdrawing the needle from the sole, this arm draws the strand back with the needle, thereby bringing the strand from the shuttle-carrier on the other 30 side of the sole into and part way through the sole, leaving the looping-point of the two strands about in the middle of the sole and drawing the coiled strands compactly together. The backward movement of this arm 35 also serves to take off from the bobbin j' enough of the strands to make the next crossing through the sole.

On the outer side of the needle-bar, extending about one-third of its length, is fixed a 40 slotted plate, i , in which are set two movable studs, i' and i^2 , which have motion with the needle-bar and strike the inner end of an elbow-lever, s , carrying it forward and then backward.

45 The elbow-lever s is pivoted on a pin, i^3 , set in the top of the rail of the supporting-frame, with the outer end of the lever taking hold loosely of a lever, q , having for its fulcrum the shaft p , said lever q carrying a pawl, q' , loosely 50 attached to it. This pawl, as the lever q is moved by the motion of the elbow-lever s , engages in the teeth of the ratchet-wheel q^2 , which is also on the shaft p , and which is partially rotated by each traverse of the needle-bar h .

55 The shaft p , supported in suitable bearings on the frame of the machine, extends across it parallel to the shaft b , and on the other end of it is fixed a pinion-gear, o . This pinion-gear 60 works into the under side of a toothed rack, m . This toothed rack engages and carries forward and backward the bed m^5 , upon which the coil of cordage to be woven for a sole is secured and held while it is being woven by a clamping-plate. This bed and clamping-plate, containing the coil of cordage to be formed into

a sole, is by every movement of the shaft p imparted by the elbow-lever s carried forward, so that the next forward movement of the needle will penetrate through the coil of cordage at such distance from its last crossing as may be desired, the feed being regulated by the distance between the studs i' and i^2 . When the transverse sewing of the cordage is completed the pawl q' is raised from the ratchet-wheel q^2 , which allows the shaft p to revolve freely, and the toothed rack m is pushed back to its starting-point by the operator, and the pawl q' being dropped to its place, the machine is again ready for operation upon another coil 80 when supplied.

The machine is put in motion, when ready for work, by pressing the pulley a^2 into the pulley a' with such force that the surfaces coming in contact will so engage each other that the motion of 85 the pulley a' is communicated to the pulley a^2 , which, being firmly fixed on the shaft b , puts the machine in motion. The pulley a^2 is driven into the pulley a' by the operator turning the wheel o' sharply to the right. This wheel is on a shaft, 90 o^2 , which extends across the machine below the top rails, parallel to the main shaft e , and carries firmly fixed on it just inside of the wheel o' an elbow-lever, o^3 , one end of which is connected to the lower rail of the frame of the 95 machine by a spiral spring, o^4 . This spiral spring, being left free to act on the elbow-lever o^3 , turns the shaft o^2 over to the left. On the further end of the shaft o^2 is a disk to carry an eccentric-pin, o^6 , which works in a slot in 100 the elbow-lever o^5 . This lever is pivoted to the machine-frame, and its upright arm bears against the side of loose pulley a^2 , so that as it is pressed in one direction or the other the wheel is pressed into or released from contact 105 with the fixed wheel a' .

By securing the right-hand arm of the elbow-lever o^3 with the swinging hook o^8 , which is pivoted on the upper side of the top rail of the frame of the machine and held to the 110 arm of the elbow-lever by a light spring, o^7 , the two pulleys a' and a^2 are held in contact with each other until the hook o^8 is disengaged. When this disengagement takes place the lever o^3 is released, the spring o^4 draws down 115 the other arm, turning the shaft o^2 to the left and moving the lever o^5 away from holding the two pulleys a' and a^2 together, when they instantly become disengaged and the motion of the machine ceases. This occurs 120 when the bed, which carries the coil of cordage to be united together in the manner described, has been moved by the feed mechanism the length of the sole, when an adjustable stop, m' , on the rack m strikes the straight end 125 of the swinging hook o^8 and, overcoming the power of the spring o^7 , disengages the hook from the elbow-lever o^3 . Thus the motion of the machine is automatically stopped when the whole length of the sole has been sewed. The 130 stop on the rack can be adjusted for any length of sole which can be made on the machine.

The flat bundle of cordage which is to make the sole is wound in an oblong form, a little narrower toward the end which is to be the heel, and approximating to the shape of an ordinary leather sole. Said flat bundle is then laid on the bed made to receive it, and is secured thereon by a clamp-plate, z , Figs. 7 and 8, which plate is held down upon said bundle by turning down the nuts on the swinging 10 screws m^3 and m^4 .

The ends of the bed are formed by the angle-pieces m^{10} and m^{11} , of which the former is stationary and the latter is adjustable, in order to accommodate soles of different lengths.

15 The flat bundle of cordage which is to make a sole is secured at one side by the cover t , which is over the raceway in which the shuttle moves. On the other side is the needle-guide k , to which is attached an arm, k^* , extending along the coil 20 of cordage. The needle-guide is supported on two arms, j^1 and j^2 , which, in turn, slide in holes through supporting-blocks k^1 and k^2 , and are firmly affixed to a plate, k^3 , depending from the under side of a lever, v , which is pivoted 25 on the upper side of the middle rail of the frame of the machine. The end of this lever toward the operator is furnished with a handle for the operator to grasp, and the other end is connected by a spiral spring, v' , to a 30 block, v^2 , which is fastened on the top rail of the frame near the bevel-gear d . The natural operation of this spiral spring v' is to draw the shorter end of the lever v toward the block v^2 , thereby pressing the needle-guide k and arm k^* 35 against the edge of the coil of cordage as it lies in the bed m^5 . This pressure is removed, when desirable to do so, by the operator pushing the handle of the lever v to the left and securing it by the latch v^3 , which is firmly fixed on the 40 inside of the top rail of the frame of the machine.

n' is a table affixed to the frame of the machine, in which, under the cover t , is an opening to receive the block f^8 , in which is the 45 race for the shuttle f^9 . This shuttle contains a fibrous strand similar to that carried by the needle. This strand, which is wound on a suitable bobbin or spool, is to interloop with that carried by the eye-pointed needle, and so interlooping is drawn by the backward motion 50 of the needle-bar and the arm s^2 into the coil of cordage, the looping of the two strands being finally left at or near the middle of the flat coil of cordage.

55 All the several parts of this machine having been mentioned and referred to by letters marked on the drawings, and their uses and relations to the whole, as well as their separate functions, having been set forth, I will now describe the operation of the machine as a whole.

The flat oblong coil of cordage is secured in the bed prepared for it. The spool j is provided with its proper supply of fibrous strand, and the spool in the shuttle is also supplied 65 with strand. These two strands are to be sewed through the width of the flat coil of

cordage transversely, interlooping each other in it, and firmly securing all the convolutions of the flat coil together in the form in which the coil is laid in the bed. The two strands 70 being so arranged that they will at the proper movement of the machine interloop each other, and everything being in place ready for work, the operator turns the wheel o' sharply to the right, catching the end of the upper arm of 75 the elbow-lever o^3 into the hook-lever o^8 . This causes the pulleys a' and a^2 to engage each other and revolve the shaft b , which, through the pinion c and gear d , puts all the parts in their proper order of motion. The traversing 80 of the stud g' in the curved opening through the broad part of the needle-bar carries the needle-bar forward, driving the needle with the strand of fiber in its eye through all the convolutions of cordage, piercing through the 85 middle of all, and carrying the eye of the needle an inch or more beyond the edge of the flat coil. The motion, continuing, withdraws the needle a little, which motion forms a loop with the strand in its eye. Here the motion 90 of the needle-bar ceases for a moment, the form of opening through its broad part being such as to permit the traversing of the stud g' in it without giving it motion. While the needle-bar is thus for a moment at rest, the cam f moving, 95 the stud e^2 , traversing its irregular groove, moves the rocking shaft f^4 and carries the shuttle, with its bobbin of fibrous strand, through the loop formed by the needle. As soon as the shuttle has passed through the loop the needle-bar, resuming motion, withdraws the needle and the loop it made on the other edge of the (to be) sole, bringing the strand from the shuttle, which passed through the loop with it part way, and drawing the whole up tightly, 100 105 the point of the needle being quite outside of the guide-plate which presses the edge of the sole. The feed mechanism described is then moved by the stud i^2 striking the elbow-lever s , carrying the bed m^5 forward the distance 110 which is desired between the crossing strands. Here one revolution of the main shaft has been made; another begins, and ends with the results described. The motion continuing, the sole is sewed the whole length, as described, when 115 the adjustable stud on the rack m strikes the end of the hook-lever o^8 , disengaging its hold on the elbow-lever, and the machine stops to receive another coil to be united.

Having thus fully described the construction and operation of my machine, I claim as new and my invention—

1. A machine for making soles of the character described, comprising, in combination with a bed-plate and clamping-plate for receiving the bundle of cordage flatwise between them, an eye-pointed needle, a shuttle and operating devices for inserting binding-strands from side to side through the bundle of cordage, and mechanism, as indicated, for feeding 125 the same intermittently in the direction of its length, substantially as set forth.

2. The bed formed by a bed-plate, clamping-plate, and angle-pieces or upright projections carried by the bed-plate and capable of adjustment to regulate the distance between them, substantially as described.

3. The combination of a bed-plate, a clamping-plate, a guide pierced with a needle-hole and arranged opposite the space between said plates at the side, and a spring connected with said guide and serving to press the same toward the said plates, substantially as described.

4. The combination, with an eye-pointed needle and shuttle and operating mechanism, of the bed-plate, the pieces forming the ends of the bed, the cover to the shuttle-race, and the

needle-guide, said guide and cover being on opposite sides of said bed-plate, substantially as described.

5. In a machine of the general character described, the combination, with the eye-pointed needle, shuttle, and operating mechanism, of the bed, feed mechanism, as indicated, for moving the bed forward, and devices, as explained, for stopping the machine automatically when the bed reaches a predetermined point, substantially as described.

THOS. J. MAYALL.
